UNITED STATES PATENT OFFICE.

HORACE W. HEYMAN, OF MAPLEWOOD, NEW JERSEY.

COMBINED TEMPERATURE INDICATOR AND DRAFT REGULATOR.

Application filed December 20, 1926. Serial No. 155,892.

The present invention relates to a mechanism for controlling the furnace draft, it being located in a remote place from which point it has been found desirable to operate the furnace. In many instances it is disadvantageous to install a complicated automatic heat regulating system and yet, with sufficient changes in temperature, it is highly desirable to be able to regulate the draft without going to the furnace room. Where steam boilers are used, an automatic device is provided for shutting off the draft, and it is often necessary to open the draft manually at different times. The present invention therefore, provides a manual means for permitting the normally weighted arm to open the draft, and yet while open, permits the automatic control to shut off the draft. Movement of the manual means in the reverse direction positively closes the draft.

The present invention provides a simple and effective control mechanism for steam boilers of the above type, by means of which the draft may be opened manually from a remote point and is analogous to the invention disclosed in the co-pending application Ser. No. 132,712, wherein movement of the manual means positively opens the draft and holds it open until the means is returned to the closed position. This type is adapted for use in furnaces etc., which do not have the automatic features of steam boilers.

As noted in the above co-pending case, an object of the present invention is to provide a structure which will not only mount the temperature indicating means but also serve as a part of the means for manually controlling the furnace draft system. Simplicity and effectiveness characterize the structure herein set forth and the advantage of mounting the control upon an element which also mounts a temperature indicating means will be apparent since the draft is controlled after observation of the temperature indicating means. By providing a single mounting which secures both of the above elements, great convenience is provided.

Reference will now be had to the accompanying drawings forming a part hereof wherein:

Figure 1 is a front elevation of the present invention, showing a common mounting means for the two elements noted above.

Figure 2 is a section taken on the line 2-2 of Figure 1 and looking in the direction of the arrows.

Figure 3 is a rear elevation of the device shown in Figure 1.

Figure 4 is a diagrammatic illustration of the invention installed to operate the furnace draft of a steam boiler.

In the drawings *a* indicates a block of suitable material which may be secured to any convenient part of the frame work of a building *b* by means of screws *c*. The front of the block carries a thermometer *d* and the rear thereof is provided with a countersunk groove *e* and, in addition, a slot *f* below the groove *e*. Within the slot *f* a metallic angle piece or slide *g* is received. A cap *h* is secured within the groove *e* and confines the angle piece *g* to vertical movements, there being a spring clip *i* within a pressed out portion *j* of the cap which spring element serves to urge the metal angle piece *g* against the back of the slot *f*.

The spring *k* is secured at one end to the bottom of the angle piece *g* and at the other end to the top of the block, the points at which the spring is secured being designated respectively, as *k'* and *k''*. The rearwardly extending arm *g'* of the angle piece *g* has secured thereto a cord *l* which is connected to the furnace control rod *m*, the weights of which normally hold the draft open. When the handle portion *g''* of the angle piece *g* is moved upwardly the draft is closed, the spring *k* serving to help overcome the weighted arm *m*. By moving the handle *g''* downwardly the weights open the draft in an obvious manner. It is apparent that the specific elements forming the combination set forth herein may be arranged in a different manner without departing from the scope of the invention as set forth in the appended claims.

What I claim is:

1. In a draft control, a thermometer base, means for securing it to a wall, a manually operated slide for controlling the draft regulator of a heating plant, an outwardly projecting arm at the bottom of the slide for manual operation, an inwardly projecting arm at the top of the slide, means to connect the last named arm to the draft control means of a heating plant, a channel in the rear face of the base to receive the slide, a countersunk plate secured to the rear face to slidably secure the slide to the base, and

a spring connected to the lower end of the slide and to the upper end of the base tending to urge the slide to an off position.

2. As an article of manufacture, a draft control for a heating plant comprising a base, means for securing it to a wall, a manually operable slide for controlling the draft regulator of a heating plant, an outwardly projecting arm at the bottom of the slide for manual operation, an inwardly projecting arm at the top of the slide, means to connect the last named arm to the draft control means of the heating plant, a chan-

nel in the rear face of the base to receive the slide, a countersunk plate secured to the rear face of the base to retain the slide within the channel, a leaf spring between the plate and the slide to maintain the slide in any desired position, and a spring connected to the lower end of the slide and to the upper end of the base tending to urge the slide to an off position and to assist in manual operation of the slide.

This specification signed this 17th day of December, A. D. 1926.

HORACE W. HEYMAN.
